UNITED STATES PATENT OFFICE.

SAMUEL B. FIELD, OF HOLBROOK, MASSACHUSETTS, ASSIGNOR OF ONE-FOURTH TO PNEUMATIC SCALE CORPORATION, LIMITED, OF QUINCY, MASSACHUSETTS, A CORPORATION OF MAINE, AND THREE-FOURTHS TO WILLIAM H. DOBLE, OF QUINCY, MASSACHUSETTS.

FOLDING BOX.

1,162,466.

Specification of Letters Patent Patented Nov. 30, 1915.

Application filed November 20, 1914. Serial No. 873,092.

To all whom it may concern:

Be it known that I, SAMUEL B. FIELD, citizen of the United States, residing at Holbrook, county of Norfolk, State of Massachusetts, have invented a certain new and useful Improvement in Folding Boxes, of which the following is a specification, reference being had therein to the accompanying drawings.

10 The invention relates to an improvement in folding metallic boxes to serve as shipping cases in which the goods may be packed for shipping and which can be folded into small compass to be returned to the shipper 15 to be again used.

It has special reference to that class of such folding boxes in which the panels are each formed with an inner and an outer wall plate spaced apart from each other.

20 It is especially applicable to that class of folding boxes above described in which the box is made of six panels in which the front is hinged to the bottom and to the two ends and the top or cover is hinged to the back, 25 the front having a separable connection with the top, and the back having a separable connection with the bottom.

One object of the present invention is to provide a simple form of interengaging connection 30 between the two end panels and the top and bottom panels to retain them in rigid form when the box is set up. The top and bottom each have a tongue and groove connection with the two ends which makes 35 a tight joint and stiffens the box when the box is closed but which allows both the top and the bottom to turn on their hinges.

Another object of the invention is to provide 40 a simple form of safety lock and sealing device between the top and the front, and between the bottom and the rear panel which can be easily applied when the box is to be sealed up after being filled and which can be readily removed when the box is to 45 be unpacked and which co-operates with the said interengaging connections between the two ends of the top and bottom panels to hold the box in rigid form when set up and sealed. The seal is destroyed in opening the 50 box and thereby furnishes a tell tale to prevent anyone tampering with the box by opening the seal and closing it again unless he has an additional one of the special

forms of sealing clips, the clips themselves being simple and cheap so that it is intended 55 to use a new one every time the box is refilled.

The invention will be fully understood from the following description taken in connection with the accompanying drawings 60 and the novel features thereof will be pointed out and clearly defined in the claims at the close of the specification.

In the drawings, Figure 1 is a plan view of a box embodying the invention. Fig. 2 65 is a front elevation of the box shown in Fig. 1. Fig. 3 is an end view of the box shown in Fig. 1. Fig. 4 is a section on line 5—5 of Fig. 1 on an enlarged scale but showing the sealing clip slipped into place but before it is bent down into sealing form. Fig. 5 is a section on the same line 5—5 of Fig. 1 after the clip has been bent down into its sealing form. Fig. 6 is a section on line 6—6 of Fig. 1 on an enlarged scale and partly broken 70 away. Fig. 7 is a detail plan of one of the sealing clips shown in Fig. 4 before it is attached. Fig. 8 is a section on line 8—8 of Fig. 7.

Referring now to the drawings, the six 80 panels referred to are the front A, the back B, the right and left-hand ends C and D respectively, the cover or top panel E, and the bottom F. The front A has a separable connection with the top panel E by means of 85 the sealing clips hereinafter to be described and the back B has a similar connection with the bottom F. Each of the panels is made with an inner wall plate 1 and an outer wall plate 2 having a space between 90 them which is preferably braced or stiffened with corrugated plates between the walls, as for instance, in the manner shown in Patent No. 941,013 dated November 23, 1909 or as shown in application filed by me July 19, 95 1913, Ser. No. 779,945. In the device of the present invention, however, in addition to the intermediate corrugated plates the top and bottom edges of the two end panels are provided with channel plates of a special 100 form which engage between the inner and outer wall plates and project above and below the top and bottom edges respectively to interengage with channel plates of another special form which constitute the ends 105 of the top and bottom plates respectively.

- The front A is hinged to the bottom F and to the ends C and D, and the top E is hinged to the back B all in such manner as to permit the top panel to be folded over against the outer face of the back and the bottom to be folded up against the outer face of the front and then the box can be collapsed by reason of the hinge connection of the two end panels with both the front and the back.
- 10 Any suitable form of hinge connection may be employed. One form of suitable hinge connection for the double wall box is shown in my application Ser. No. 779,945 above mentioned.
- 15 In the form of hinge connection between the panels shown in the drawings, the bottom panel F has on its front edge a hinge pin 28 and the front panel A has on its bottom edge a hinge pin 29. Said two hinge pins are connected together by a series of links 30 so that the bottom panel may be folded up against the front face of the front panel.

The top panel E has on its rear edge a hinge pin 31 and the rear panel B has on its upper edge a hinge pin (not shown), said two hinge pins being connected together by a series of links 32 in a similar manner to that in which the front and bottom panels are hinged together so that the top panel E may be folded over against the rear face of the rear panel B.

The front panel A and the left-hand end D as viewed in Fig. 2 are hinged together by a hinge pin 33 passing through eyes 34 on the end edge of the front panel A and eyes 35 on the adjacent edge of the end panel D. The rear edge of the opposite end panel C is hinged to the adjacent edge of the rear panel B in a similar manner to that 40 in which the front panel A is hinged to the end panel D just above described.

The front panel A and the right-hand end panel C are hinged together by a hinge pin 36 which passes through eyes 37 on the 45 right-hand edge of the front panel A and through a series of eyes 38 which project at a right angle offset from the adjacent front end of the end panel C to allow the end panel C to swing around and fold 50 against the inner face of the front panel A when the box is collapsed.

The rear panel B and the left-hand end panel D are hinged together in a similar manner to that by which the front panel A 55 and the end panel C are hinged together.

Now when the top panel E is folded over against the rear panel B and the bottom panel F is folded up against the front face of the front panel A, the remaining four 60 panels may be collapsed by a pressure which will bring the front panel A and the end panel D into alinement with each other in one plane, and bring the rear panel B and the end panel C into alinement with each 65 other in another plane, the two planes being

parallel with each other, and superimposed one upon the other.

The special form of interengaging connection between the two end panels and the top and bottom panels is shown with special 70 clearness in Fig. 6. The channel plate 3 which fits into the space between the inner and outer plates 1, 2 of the end wall is formed with an upwardly projecting roll or fold 4 which extends upwardly some distance above the inner and outer plates 1, 2 of the panel. The two sides of the channel plate 3 draw in toward each other as they extend upwardly above the ends of the plates 1, 2, as shown by the inclined portions 5, 5 and terminate in the rounded or semi-cylindrical portion 4, thus forming a tongue along the edge of the end panel. In order to stiffen the roll 4 there is preferably provided a core 6 of wire or other 85 suitable material.

The top panel E which also has an inner plate and an outer plate is formed with a notch or groove in its under side near its outer edge which is adapted to engage with the said roll 4 on the upper edge of the end panel D. Any suitable form of construction of the top panel by which such an inter-engaging notch is provided may be employed but the preferred form of construction is that which is shown in Fig. 6. In said Fig. 6 the inner and outer plates 1, 2 terminate somewhat short of the end panel D and there is inserted into the space between said two plates 1, 2 a corrugated or bent channel piece 8 which fits snugly within the space between said two plates forming a part of the panel, and is bent in such manner as to form a groove or valley 9 on the under side of the channel piece substantially the full length of the end panel D. The outer edge portion of the panel E is formed with a cap plate 10 which overlies the projecting portion of the channel plate 8 and is secured thereto and is bent inward 100 to form a groove 7 which engages with the groove in the inner face of the channel plate 8 whereby the said plate 10 is firmly secured in place. Preferably this groove is like a broad V, being shown as forming a right 105 angle. The reason why it is preferred to have the groove V shaped is because the tongue makes better contact with the sides of the groove. The purpose of the cap plate is to give additional strength and take 110 the wear at the corners. The channel plate 8 as well as the other channel plates referred to in the specification are all soldered or otherwise firmly secured in proper place between the inner and outer plates so 115 that they shall not slip out. The said channel plate and cap plate are both a little shorter at each end than the end panels D and C. The end panel is provided with angular filling plates 39 at one end both at 120

125 130 135 140 145 150 155 160 165 170 175 180 185 190 195 200

top and bottom to fill the gap, and the gap at the other end is filled by the angular filling plates 40 at opposite corners both of the top panel E and of the bottom panel F. 5 The lower edge of the end panel D and the contiguous portion of the bottom panel F are constructed in the same manner as the upper edge of the end panel D and the co-engaging edge of the panel E above described. 10 The end panel C is an exact duplicate of the end panel D and the co-engaging portions of the top E and of the bottom F therewith are also constructed in the same manner as the co-engaging portions of said 15 top and bottom panels which engage with the end panel D.

The front edges of the plates 1, 2 of the top panel E stop a little short of the inner face of the front panel A, (see Figs. 4 and 20 5,) and into the space between the two plates 1, 2 of the said top panel at its front edge there is inserted a channel piece 11 which fits snugly between said plates 1, 2 and is firmly secured by soldering or otherwise as above 25 described and has a projecting offset loop portion of peculiar form of construction to form a vertical back rest 12 for the upper part of the channel piece of the front panel A and to form a horizontal portion 13 which 30 rests upon the upper end of the channel piece of the front panel A. From the front lower edge of the horizontal portion 13 of the channel piece 11 the loop thereof has a backward and upward sloping portion 14 35 which rises somewhat higher than the upper surface of the outer plate 2 of the top panel E and then has a downwardly extending shoulder portion 15 and is then bent to form a part of the shank of the channel piece 11. 40 The said shoulder portion 15 of the channel piece 11 forms an end abutment for the outer plate 2 of the top panel E while the vertical portion 12, as already described, forms a stop or rest for the inner face of the 45 front panel A and the horizontal portion 13 rests on top of the front panel A. Preferably the space of the loop formed by the bent portions 13, 14, 15 is filled by a core 16 of metal or other suitable stiffening material. The inner and outer plates 1, 2 of the 50 front panel A terminate somewhat short of the under side of the top panel and into the space between said two plates is inserted a channel plate 17 which projects above the plates 1, 2 and forms a part of the panel. 55 The outer face of the upwardly extending portion of said channel plate 17 above the top of the outer plate 2 of the panel A is formed with a reentrant bend making an inwardly inclined portion 18 and terminating in an outwardly extending loop portion 19. Said loop portion 19 has a flat upper face 60 on which rests the flat portion 13 of the channel piece 11. A stiffening core 21 is inserted into the loop of the channel piece 17.

The lower edge of the front panel A has a hinge connection, as already stated, with the front edge of the bottom panel F and the rear edge of the top panel E has a hinge connection with the top edge of the rear panel B. The rear edge of the bottom panel F and the bottom edge of the rear panel B are constructed and provided with channel pieces corresponding respectively to the construction of the front edge of top panel E and 75 top edge of the front panel A. It is therefore deemed unnecessary to repeat the description and detailed illustration of those portions of the back and bottom panels. 80

An angular filling member 40 is formed with an arm 42 which enters and closes the end of the channel member 8 of the top panel E and has another arm 43 which enters and closes the end of the channel member 11 on the front edge of the panel plate E and the head of said angular member 40 fills the notch at the ends of said channel plate, as shown in Fig. 1. There are two of these angular filling members 40 at diagonally opposite corners of the upper panel E, as shown in Fig. 1. At the other two diagonally opposite corners of said panel E there are two other angular filling members each having the arms 44, 45, the arm 44 filling the opposite end of the channel plate from that which is filled by the arm 42 of the filling member 40, and the arm 45 filling the opposite end of the channel member 11 from that which is filled by the arm 43. 95 100

When the box is set up and squared out it is important to have some fastening or binding mechanism to fasten together the front edge of the top panel E and the top edge of the front panel A and also some means to secure together the rear edge of the bottom panel F and the bottom edge of the rear panel B. Similar fastening means are used in both places and will now be described. This fastening means consists of one or more 105 clips with which the connection can readily be made and which after the connection is made are intended to be bent down in order to make them secure during transportation and which can be bent up again to detach 110 them. These clips are cheap and it is intended to make them of such material that they are sufficiently strong and tough enough to be used once, but will not stand the necessary bending for a second use. These clips 120 are made out of sheet metal which may be flexed under the blow of a hammer but have little or no resiliency so that they will retain any form to which they are bent. The clip has a body portion 22 which is adapted to lie over the front inclined face 14 of the channel piece 11 and terminates at its lower end in a hook portion 23 which is adapted 125 to go over the outer edge of the loop portion of the channel piece 17 and hook under 130

the flat under face of said loop, as shown in Fig. 4. The other end of the body portion of the clip is bent to form a hook portion 24 which engages over the top edge of the 5 channel piece 11 and comes down behind it as shown in Fig. 4, but extends at an angle to the vertical portion 15 of said channel piece so that it requires a bending of the hook portion 24 in order to bring it down 10 flush against the face of the said portion 15. It also has an ear 25 which extends up at about a right angle to the portion 24 and stands at an acute angle to the outer plate 2 of the top panel. The clips in detached 15 condition are of the shape shown in Fig. 4 and in this form they can be easily engaged with the two channel members 11, 17; as shown in Fig. 4. Then in order to securely fasten the clip in place the portion 24 is bent 20 down more sharply as shown in Fig. 5 to bring the inner face of the portion 24 in contact with the vertical face 15 of the channel piece 11 and to bring the ear 25 flat down into contact with the outer face 2 of the 25 panel E. This can be done by the use of a hammer or other suitable tool and does not require other fastening because the metal is of such character that it retains its bent form. Preferably the ear 25 is provided 30 with a hole 26 to serve as an engaging place for a screw driver or other suitable tool to bend up the ear 25 in order to release the clip. Preferably these clips are made of relatively short length and a plurality of 35 them are used, as shown in Figs. 1 and 2 instead of employing one long clip. It is desirable to make the clips of rather thin sheet material and in order to give them the requisite stiffness it is preferable to stamp 40 them up so as to form ribs 27. It is also preferable to make them of a metal so treated that it will have a degree of brittleness which will allow the clips to be bent into the sealing form without breaking but 45 which will be sufficiently weakened in bending the clip to remove it so that it cannot be used a second time. One way of doing this is to make a core of relatively soft metal and case hardening the surface, or by tempering it to form what is sometimes termed half hard metal. Similar clips to those 50 above described for securing the contiguous edges of the front and top together are employed for securing together the contiguous 55 edges of the back and bottom. In order to prevent the clips from sliding off endwise after they have been bent down into operative condition, the channel member 14 is formed with lugs or shoulders 41, one on 60 either side of each clip, to limit the possible range of movement. The box when set up is perfectly rigid as the interengaging portions formed by the channel pieces serve to hold the various panels in place.

65 While the sealing clip above described is

the preferred form of seal to be used, it is obvious that the particular form of seal may be varied. Any suitable form of seal which engages the projecting portions of the adjacent edges of said two adjacent 70 panels, and is of such a character that it is practically destroyed when the seal is opened to disengage the two panels from each other comes within the scope of this invention and it is intended that the claim 75 shall be construed to cover such variable form of seal.

What I claim is:

1. In a folding metallic box, a panel composed of a hollow wall having a longitudinal indentation to form a channel groove near the edge thereof, in combination with another panel composed of inner and outer plates spaced apart from each other, and a closure plate fitted to bridge the space between two adjacent edges of said inner and outer plates of said second panel and having a projecting fold which engages with the said groove in said first mentioned panel. 80

2. In a folding metallic box, two opposite parallel panels each composed of a wall having a longitudinal indentation to form a groove near the edge thereof, in combination with a third panel at right angles to and extending from one to the other of said first two panels, said third panel being composed of inner and outer plates spaced apart from each other, and closure plates to bridge the space between the inner and outer plates of said third panel at two opposite edges of the panel and having projecting folds which engage with the said grooves in said first two panels. 90

3. In a folding metallic box, two opposite parallel panels each composed of an inner plate and an outer plate spaced apart from each other and a closure plate which closes the edge opening between said inner and outer plates, said closure plate being formed with a longitudinal indentation near the edge of the inner face, in combination with a third panel at right angles to and extending from one to the other of said first two panels, said third panel being composed of inner and outer plates spaced apart from each other, and closure plates to bridge the space between the inner and outer plates of said third panel at two opposite edges of the panel and having projecting folds which engage with the said grooves in said first two panels. 105

4. In a folding six sided metallic box, two opposite parallel panels each having a longitudinal indentation near each of two opposite edges to form grooves, in combination with two other panels parallel with each other and at right angles with said first two panels, each of said second pair of panels being composed of inner and outer plates 110

125

130

spaced apart from each other, closure plates to bridge the space between the inner and outer plates at two opposite edges of each of said second pair of panels and having 5 projecting folds which engage with the said grooves in said first pair of panels, and a third pair of panels opposite to and parallel with each other, each of said third pair of panels being hinged to both of said second 10 pair of panels on two opposite edges, one of said first pair of panels being hinged to one of said third pair of panels and the other of said first pair of panels being hinged to the other of said third pair of 15 panels, the hinge line of one of said first pair of panels being diagonally opposite the hinge line of the other of said first pair, the edges of said first pair which are opposite the hinge edges of said first pair of panels 20 having a separable connection with the adjacent edges of the third pair of panels.

5. In a folding six sided metallic box, two opposite parallel panels each composed of inner and outer plates spaced apart from 25 each other, each of said panels having a longitudinal indentation near each of two opposite edges to form grooves, in combination with two other panels parallel with each other and at right angles with said 30 first two panels, each of said second pair of panels being composed of inner and outer plates spaced apart from each other, closure plates to bridge the space between the inner and outer plates at two opposite edges of 35 each of said second pair of panels and having projecting folds which engage with the said grooves in said first pair of panels, and a third pair of panels opposite to and parallel with each other, each of said third pair of 40 panels being hinged to both of said second pair of panels on two opposite edges, one of said first pair of panels being hinged to one of said third pair of panels and the other of said first pair of panels being hinged to the other of said third pair of panels, the hinge line of one of said first pair of panels being diagonally opposite the hinge line of the other of said first pair, the edge of each 45 of said third pair of panels opposite its hinged edge having a channel plate which closes the space between the inner and outer plates and has a projecting portion formed with an indented groove to serve as a catch, and having a portion which serves as a bearing 50 surface for the adjacent panel, each of said first pair of panels having at the edge opposite its hinged edge a channel plate which closes the space between the inner and outer plates and has a projecting offset portion which engages the channel plate of the 55 adjacent edge of one of said third pair of panel plates, and a plurality of clips which are fitted to engage with the channel plates on the said adjacent coöperating edges of the 60 first and third pair of panels.

7. In a folding metallic box having panels composed of inner and outer plates spaced apart from each other, one of said panels being formed with a reentrant longitudinal 65 valley parallel with the edge, and one of the adjacent coöperating panels being composed of inner and outer wall plates spaced apart from each other and having projecting longitudinally of its edge intermediate the inner 70 and outer plates a tongue member which engages with said valley in the said first panel.

8. In a folding metallic box having panels composed of inner and outer plates spaced apart from each other, one of said panels having a closure plate attached to the edge thereof, said closure plate being bent in its inner face near the edge thereof to form a longitudinal groove and one of the adjacent coöperating panels having inner and outer 75 wall plates spaced apart from each other and having in one edge a closure member formed of a plate bent to form a channel piece which is connected with the inner and outer plates of said panels and having an 80

each other, each of said panels having a longitudinal indentation near each of two opposite edges to form grooves, in combination with two other panels parallel with each other and at right angles with said first two 70 panels, each of said second pair of panels being composed of inner and outer plates spaced apart from each other, closure plates to bridge the space between the inner and outer plates at two opposite edges of each 75 of said second pair of panels and having projecting folds which engage with the said grooves in said first pair of panels, and a third pair of panels opposite to and parallel with each other, each of said third pair of 80 panels being hinged to both of said second pair of panels on two opposite edges, one of said first pair of panels being hinged to one of said third pair of panels and the other of said first pair of panels being hinged to the other of said third pair of panels, the hinge line of one of said first pair of panels being diagonally opposite the hinge line of the other of said first pair, the edge of each 85 of said third pair of panels opposite its hinged edge having a channel plate which closes the space between the inner and outer plates and has a projecting portion formed with an indented groove to serve as a catch, and having a portion which serves as a bearing 90 surface for the adjacent panel, each of said first pair of panels having at the edge opposite its hinged edge a channel plate which closes the space between the inner and outer plates and has a projecting offset portion which engages the channel plate of the 95 adjacent edge of one of said third pair of panel plates, and a plurality of clips which are fitted to engage with the channel plates on the said adjacent coöperating edges of the 100 first and third pair of panels.

7. In a folding metallic box having panels composed of inner and outer plates spaced apart from each other, one of said panels being formed with a reentrant longitudinal 105 valley parallel with the edge, and one of the adjacent coöperating panels being composed of inner and outer wall plates spaced apart from each other and having projecting longitudinally of its edge intermediate the inner 110 and outer plates a tongue member which engages with said valley in the said first panel.

8. In a folding metallic box having panels composed of inner and outer plates spaced apart from each other, one of said panels having a closure plate attached to the edge thereof, said closure plate being bent in its inner face near the edge thereof to form a longitudinal groove and one of the adjacent coöperating panels having inner and outer 115 wall plates spaced apart from each other and having in one edge a closure member formed of a plate bent to form a channel piece which is connected with the inner and outer plates of said panels and having an 120

outwardly projecting tongue arranged and constructed to engage with said longitudinal groove in the said first panel.

9. In a folding metallic box having panels composed of inner and outer plates spaced apart from each other, one of said panels having a closure plate attached to the edge thereof, said closure plate being bent in its inner face near the edge thereof to form a longitudinal groove with flaring sides, and one of the adjacent coöperating panels having inner and outer wall plates spaced apart from each other and having in its upper edge a closure member formed of a plate 10 bent to form a channel piece which is connected with the inner and outer plates of said panel and having an outwardly extending tongue arranged and constructed to engage with said longitudinal groove in the 15 said first panel, said tongue being formed with a semi-cylindrical edge.
10. In a folding metallic box having panels composed of inner and outer plates spaced apart from each other, one of said panels having a channel piece inserted and secured in the space between the said inner and outer plates at the outer edge thereof, said channel plate being bent to form on its inner face near the outer edge thereof a 20 longitudinal groove, a cap piece formed of sheet metal which fits over the outer end of said channel piece and is bent to form a groove which fits into the groove in said channel piece, in combination with a second 25 panel composed of inner and outer plates and a channel piece which is inserted into the edge between the inner and outer plates of the said panel, said channel piece having an outwardly extending roll which engages 30 with the said longitudinal groove in the said first panel.

11. In a folding metallic box, a panel composed of an inner and an outer plate spaced apart from each other, a channel member inserted into the open space at one 45 edge between said inner and outer plates, said channel member being formed of a metal plate which is bent to form a closure member which fits between said inner and outer panel plates and has an outwardly extending offset portion with an inwardly extending bend which makes two shoulders, to bear respectively against the edge and inner face of an adjacent panel, in combination

with a coöperating panel composed of two parallel plates spaced apart from each other and a channel piece fitted into the edge of said panel and having an outwardly extending portion which engages with said two shoulders of the channel piece in said first panel, said channel piece of the first panel being formed with an outside shoulder which is adapted to engage with one hook end of a hook shaped clip and the channel piece of the second panel being formed with a reentrant bend forming a shoulder which is adapted to engage with the other hook end of said clip.

12. In a folding metallic box, two coöperating panels forming two adjacent sides of the box, one of said panels having at the edge adjacent the said coöperating panel an outwardly extending off-set portion formed with a bend which makes a shoulder to bear against the edge of said adjacent panel and another shoulder which bears against the inner face of said adjacent panel, and having on the outer face a shoulder which is adapted to engage with a clip, said coöperating panel having at its edge which is adjacent to said first panel a projecting portion which has a reentrant bend in its outer face to engage with the same clip which engages the said first panel.

13. In a folding metallic box two coöperating panels forming two adjacent sides of the box each of said panels having at the edge which is adjacent to the said coöperating panel a shoulder portion which bears against the edge of the other of said two panels, said two panels having at their adjacent edges projections adapted to be engaged by a seal.

14. In a metallic box, a panel composed of inner and outer plates spaced apart from each other, channel members for closing the spaces between the said inner and outer plates on two adjacent edges of the panel, and an angular member to fill the gap formed at the corner of the panel by two adjacent channel members.

In testimony whereof I affix my signature, in presence of two witnesses.

SAMUEL B. FIELD.
